2 Sheets-Sheet 2

FIG. 5.

INVENTOR

BY *Wm. M. Kelly,*
Watson, Cott, Moore & Grindle,
ATTORNEY

UNITED STATES PATENT OFFICE.

WILLIAM M. KELLY, OF WESTFIELD, NEW JERSEY.

SNAP GUIDE.

Application filed April 15, 1927. Serial No. 184,120.

The present invention relates to side register mechanism for use in paper handling machines, such as sheet feeders for printing presses. More particularly the invention relates to that type of side register mechanism comprising upper and lower jaws reciprocating transversely to the path of the sheets and acting to grasp an edge of the sheet and shift the sheet laterally into correct register with a printing cylinder or other mechanism operating on the sheets and then to release the sheet and move back into position to operate on a succeeding sheet. The object of the invention is to simplify the construction and improve the action of side register mechanism of this type.

A practical embodiment of the invention is illustrated in the accompanying drawings, of which:

- 20 Figure 1 is a side elevation;
- Figure 2 is a top plan view;
- Figure 3 is a central vertical longitudinal section;
- Figure 4 is a fragmentary vertical section

25 through the front end of a paper feed board, showing the side register mechanism in end elevation, and

Figures 5 and 6 are perspective views of certain elements of the mechanism detached. 30 In Figure 4, 10 designates the feed board of a printing press and 11 the feed board extension. A plate 12 is secured under the feed board and a bar 14 carrying side register mechanism embodying the present invention is slidably mounted on plate 12 in any suitable fashion. Bar 14 is reciprocated longitudinally in timed relation to the operation of the press in any approved manner, for example, by mechanism such as shown in 35 my application, Serial No. 490,290, filed August 6, 1921. As the present invention relates solely to the construction of the sheet handling mechanism mounted on bar 14, a complete understanding of the invention 40 would not be facilitated by the showing of a specific mechanism for reciprocating the bar.

Figure 6 shows detached the base or frame of the side register mechanism. This frame consists of a single piece of metal formed on 45 its under side with a longitudinal channel 15, providing inturned, or reentrant, flanges 16, which when the frame is mounted on bar 14 engage the under side of lateral flanges 17 of said bar, see particularly Figure 4. The frame is slotted through vertically at 18 from a point near the center to

and through one end, and is undercut at said end to a horizontal plane 19 coincident with the plane of the top wall of slot 15 and to a vertical plane 20 intermediate the ends of slot 18. The end wall 21 of slot 18 is downwardly inclined, as shown in Figure 3. The ends of the laterally spaced members 22 formed by slot 18 are beveled at 23 in a plane extending downwardly and inwardly with respect to the frame, for a purpose which will hereinafter appear.

A plate 24 of the form clearly shown in Figure 5 is secured to the top wall of slot 15 by a screw 25 which is threaded in the frame and engages a countersunk hole in the inner end of the plate, the head of the screw being flush with the under surface of the plate. Plate 24 is provided with lateral lugs 26 engaging the sides of the frame, whereby lateral displacement of the plate is prevented. The top surface of the plate is cut away, as shown in Figure 5, and the projecting ends and sides of the plate beyond lugs 26 are beveled as shown at 27.

A movable jaw, or hammer, 28 is mounted in the space between the members 22 of the frame so as to have a pivotal movement to and from plate 24 to clamp and unclamp sheets against said plate. For this purpose the hammer is secured to a pin 29 pivoted in bearings in members 22 and projecting at both ends outside of said members. Arms 30 having bifurcated outer ends are secured to the projecting ends of pin 29 and pivoted in the bifurcated ends of said arms are heads 31 of rods 32 which extend through apertures in heads 33 of a cylindrical pin 34 supported in a horizontal slot 35 cut in the inner face of an upwardly projecting part of the frame. 95 Coil springs 36 surround rods 32 and bear at their ends against the heads 31 and 33, respectively.

In Figure 3 it will be observed that the plate 24 rests on the top surface of bar 14 with the inturned flanges 16 of the frame engaging the lateral flanges 17 of the bar. The engagement is sufficiently loose to permit the frame with the parts carried thereby to be slid along the bar 14 to any desired position of adjustment. In order to clamp the frame to the bar when adjustment has been made a set screw 37 is threaded in an aperture 37' of the frame with its end adapted to engage the top of bar 14. This simple adjustment enables the mechanism to operate on sheets of varying widths, and is the

only adjustment that the mechanism requires.

In Figures 1 to 4, hammer 28 is shown in closed position. At the beginning of a registering operation the hammer is in open position with its tail end resting on the stop screw 38. At this time bar 14 is at the limit of its movement toward the left, looking at Figures 1 to 3. When a sheet passing over the feed board approaches the position for registration, bar 17 moves to the right causing the edge of the sheet to enter the throat defined by the inclined surfaces 23 and 27 of members 22 and plate 24, respectively, and when the sheet has fully passed into said throat an adjustable arm 39 on an oscillating shaft 40 moves down against the hammer 28 and moves the hammer until the lines of action of springs 36 pass above the pivot 29, whereupon the springs cause the hammer to snap down on the sheet and firmly clamp it against plate 24. The bar 14 continuing to move to the right the sheet is thus positively shifted laterally into correct registration, whereupon the arm 39, which in the meantime has moved up, again moves down and engages the tail end of the hammer, raising the hammer until the lines of action of springs 36 pass below the pivot 29, whereupon the hammer moves to its fully open position with a quick snap action, the movement in this direction being limited by engagement of the tail end of the hammer with the stop screw 38. The bar 14 now moves towards the left to its initial position, positioning the mechanism for operation on a succeeding sheet.

It is not deemed necessary or desirable to show herein a specific means for operating shaft 40, as the present invention is not concerned with such mechanism. Mechanism suitable for this purpose is fully shown and described in my copending application referred to above.

It will be clear from the foregoing that the side register mechanism embodying the present invention is positive and accurate in its action and of extreme simplicity in its construction. Modifications of course may be made in the specific construction shown and described without changing the essential mode of operation, and it is not intended to limit the invention by any specific description of details.

Having thus described my invention what is claimed as new and desired to be procured by Letters Patent is:

1. A sheet registering mechanism comprising, in combination, a member reciprocating transversely with respect to the path of the sheets having a lower sheet clamping surface, a jaw on the member above said surface pivoted on an axis substantially parallel to said path, means operating in a plane transverse to the path of said member for

initiating the closing and opening movements of the jaw at certain points in the path of reciprocation, and spring means for completing the movements and holding the jaw in either closed or open position. 70

2. A sheet registering mechanism comprising, in combination, a member reciprocating transversely with respect to the path of the sheets having a lower sheet clamping surface, a jaw on said member above said surface pivoted on an axis substantially parallel to said path and having a tail portion extending on the opposite side of the pivot, an oscillating finger above said jaw adapted to move down against the jaw at 80 one point in the path of reciprocation and against said tail at another point, to initiate the closing and opening movements of the jaw, and spring means for completing the movements and holding the jaw in either 85 closed or open position.

3. A sheet registering mechanism comprising, in combination, a bar reciprocating transversely to the path of the sheets, a frame slideable on the bar, means for clamping the frame to the bar, the frame being provided with upper and lower members forming a throat adapted to receive the edge of a sheet, a jaw in the throat pivoted on an axis substantially parallel to said path 90 adapted to clamp sheets against said lower member, a part rigid with the jaw extending on the opposite side of the pivot, an oscillating finger adapted to move down against the jaw at one point in the path of reciprocation and against said part at another point, to initiate the closing and opening movements and springs for completing the movements and holding the jaw in either 95 closed or open position. 100

4. A sheet registering mechanism comprising, in combination, a bar reciprocating transversely to the path of the sheets having lateral longitudinal flanges, a block formed with a longitudinal groove in its under side 110 providing inturned flanges engaging the under sides of the lateral flanges, a set screw threaded in said block with its end adapted to abut the top of said bar, whereby the block may be clamped to the bar at any desired position, sheet engaging mechanism on the block including a jaw pivoted on an axis substantially parallel to the path of the sheets, and means for operating said jaw at 115 certain points in the path of reciprocation. 120

5. Sheet registering mechanism, comprising, in combination, a bar reciprocating transversely to the path of the sheets, a block slideable on the bar, means for clamping the block to the bar, the block being 125 formed with laterally spaced members having ends downwardly and inwardly beveled, a plate secured to the block below said members forming therewith a throat adapted to receive the edges of the sheets, a transverse 130

shaft pivoted in bearings formed in the sides of said members, a jaw between the members fixed on said shaft adapted to clamp sheets against said plate, an arm fixed on a projecting end of said shaft, a spring acting against said arm having a line of action passing above and below said shaft when the jaw is in closed and open positions, respectively, and means for operating said jaw at 10 certain points in the path of reciprocation.

6. Sheet registering mechanism comprising, in combination, a reciprocating frame provided with upper and lower members forming a throat adapted to receive the edge 15 of a sheet, a jaw in the throat pivoted on an axis at right angles to the path of reciprocation adapted to clamp sheets against said lower member, a part rigid with the jaw extending on the opposite side of the 20 pivot, an oscillating finger adapted to move down against the jaw at one point in the path of reciprocation and against said part at another point, to initiate the closing and opening movements of the jaw, and spring 25 means for completing the movements and holding the jaw in either closed or open position.

7. Sheet registering mechanism comprising

ing, in combination, a bar reciprocating transversely to the path of the sheets, having lateral longitudinal flanges, a block formed with a longitudinal groove on its underside providing inturned flanges adapted to engage the under side of the lateral flanges, a set screw threaded in said block 30 with its end adapted to abut the top of said bar, said block being formed with laterally spaced projections having downwardly and inwardly beveled ends, a plate secured against the top wall of said slot extending 40 below said projections and forming therewith a sheet receiving throat, a jaw pivoted between said projections adapted to clamp sheets against said plate, said jaw having a tail extending on the opposite side of its 45 pivot, an oscillating finger adapted to move down against the jaw at one point in the path of reciprocation and against the tail at another point, to initiate the closing and opening movements, and spring means for 50 completing the movements and holding the jaw in either closed or open position.

In testimony whereof I hereunto affix my signature.

WILLIAM M. KELLY.
